(57) **CLAIM**

The ornamental design for a cornhole set having beer pong and golf game board as shown and described.

DESCRIPTION

FIG. 1 is a top, left perspective view of a cornhole set having beer pong and golf game board showing my new design, depicting only the cornhole and beer pong board separately for complete disclosure;

FIG. 2 is bottom left perspective view thereof;

FIG. 3 is a right side view thereof;

FIG. 4 is a left side view thereof;

FIG. 5 is a top plan view thereof;

FIG. 6 is a bottom plan view thereof;

FIG. 7 is a back view thereof;

FIG. 8 is a front view thereof;

FIG. 9 is a bottom plan view of the cornhole set having beer pong and golf game board in a collapsed condition;

FIG. 10 is a side view thereof, the second side view being a mirror image thereof; and,

FIG. 11 is a perspective view of the cornhole set having beer pong and golf game board having the golf game board installed thereon for complete disclosure.

The broken lines illustrate portions of the cornhole set having beer pong and golf game board that do not form a part of the claimed design.
